SUSPENSION DEVICE FOR CONTAINER

Naurice M. Nessel, Palatine, and Theodore H. Gewecke,
Glenview, Ill., assignors to Baxter Laboratories, Inc.

Application May 4, 1954, Serial No. 427,611

4 Claims. (Cl. 248—318)

This invention relates to a suspension device for a container and, more particularly, to a bail and band for a parenteral container.

In the past it has been a customary practice to use a wide metal band mounted in a peripheral recess in the container as a means for fastening a bail thereto which, in turn, permits the container to be suspended during the period that the contents of the container are being administered. The band is ordinarily formed into a hoop by inserting one end of the band which has been previously shaped into a tongue into a hole provided in the opposite end of the band. The inserted tongue is then crimped to secure the band in a snug position in the peripheral recess. In addition, the band is provided with a pair of openings, so spaced as to be diametrically opposed when the band is closed. The ends of a wire bail are inserted into these openings.

The type of bail and band described above is cumbersome to assemble by hand or, if assembled by machine, a complex arrangement of feeding and working parts is required.

The suspension device of our invention has the significant advantage of being easily installed by machine on a parenteral container. Appreciable savings in the cost of metal and fabrication of the component parts of our new suspension device can also be achieved.

Essentially, our invention is adapted to be used in combination with a parenteral container, the container being provided with a peripheral groove or recess near its base. Ordinarily, parenteral containers are cylindrical in form and constructed of glass, so that the peripheral groove can be readily molded into the container. The groove is of such a nature as to permit the mounting of a wire band therein. The ends of the wire band are then secured together to form a hoop or closed circle of wire. A resilient bail member is clamped to the container by the wire band. The bail member is provided with enlarged end portions which permit securing of the otherwise positionable bail member in place underneath the wire band.

Our invention will be described in conjunction with the accompanying drawing in which:

Fig. 1 is a perspective view of a parenteral container equipped with the suspension device of our invention; Fig. 2 is a fragmentary cross sectional view taken along line 2—2 of Fig. 1; and Fig. 3 is an elevational view of a parenteral container equipped with the bail and band of our invention, but before the bail is locked in place.

Referring to the drawing, a parenteral container 10 is suspended by our suspension device, generally designated 11, on an independent support means 12. The support means 12 may be of any conventional form known to the art and forms no part of our invention. For example, when parenteral solutions are to be administered on the battlefield, the container may be supported from a rifle with its barrel or bayonet inserted into the ground.

The container 10 is provided with a peripheral groove

2

13 adjacent its base. Groove 13 is of a size adapted to receive a wire of sufficient diameter to support the weight of the container. The location of peripheral groove 13 with respect to the base is uncritical, so long as it is 5 above the center of gravity of the inverted, filled container. Mounted in groove 13 is wire band 14. Located between wire band 14 and container 10 are the end portions of bail member 15. Bail member 15 may be constructed of any resilient material such as a plastic, 10 and in the preferred form is a vinyl chloride-acetate strap.

As best seen in Fig. 2, bail member 15 is provided with enlarged end portions 16 which permit the bail member to be locked or secured in place under wire band 14 and also cause band 14 to fit snugly in groove 13 without special tightening. In the preferred embodiment, the end portions of the strap are characterized by a gradually increasing thickness, with the ends themselves being provided with a lateral rib or snubbed portion 16a. Thus the thickness of the strap tapers inwardly 20 the ends. The same effect may be achieved by using a bail having cross sectional shapes other than rectangular as, for example, circular with the diameter gradually increased toward the ends thereof.

However, it is to be noted that the bail may be secured 25 by other methods, as by wrapping the end portions of the bail one or more times around the band or by looping the end portion around the band and securing the loose end portion of the bail to the portion of the bail above the band, as by heat sealing, stapling, or the like.

The ends of wire band 14 may be secured together in 30 any conventional manner known to the art. In the preferred embodiment, container 10 is provided with an additional recessed portion 17 adjacent peripheral groove 13. The size of this recess is sufficient to permit the joining together of overlapping ends 18 of wire band 14 by means of welding or brazing. Securing of the overlapping ends together can be readily achieved by applying 35 spot-welding jaw means to them which will clamp the ends together and spot weld them in place, as at 19.

The suspension device of our invention can readily be 40 assembled on a container. For example, the vinyl strap constituting bail 15 is laid across the base of container 10, the container being in an inverted condition. The end portions 16 of bail 15 will then depend adjacent the side of container 10. Wire band 14, which may be preformed to slightly less than the outer diameter of container 10, is then slipped over container 10 and snapped into position in groove 13, whereupon the overlapping 45 end portions 18 of band 14 are secured together.

If the wire constituting band 14 is fed around container 10 from a wire-forming machine, it is preferred to provide container 10 with a spiral groove 13 in order to prevent the ends of band 14 from butting against each other. Such butting would prevent the band from fitting 55 into groove 13. The ends of the wire band can also be prevented from butting against each other by making the width of groove 13 about twice the diameter of wire band 14.

In this connection, it is important to note that the band does not require any special tightening because the tapered end portions of the bail, shown best in Fig. 2, act as shims when the bail is pulled away from the base 60 of the container.

A problem has existed with respect to supporting a container of this type in such a manner that twisting or 65 rotating of the container is avoided while it is supported in suspended position. In the dispensing of parenteral fluids from the container, a tube is attached to the closure of the container and a needle is fixed to the lower free end of the tube, the needle being inserted into the arm of the patient and secured thereto by tape, etc. Un-

der such circumstances, it is of great importance that the container be restrained against twisting or turning. With the structure shown, the wide band 11, when placed in supporting position, as illustrated in Fig. 1, grips diametrically-opposed portions of the container and, under the weight of the container and its contents, the broad band is effective in holding the container immobile during the dispensing operation. Further, the narrow wire band located within a relatively narrow groove, is highly effective in holding the bail in a flat or extended position against the side walls of the container, as shown best in Fig. 1.

We have found that when the bail is drawn to the position shown in Fig. 3, the bail itself is maintained in a flat extended position against the body of the container and there is no tendency for the bail under conditions of shipment to twist or to become wrinkled, etc. Further, the position of the bail as shown in Fig. 3 maintains it out of the way and enables it to be packaged readily within shipping containers, etc.

The foregoing, detailed description has been given for clearness of understanding only, and no unnecessary limitations are to be understood therefrom, as modifications will be obvious to those skilled in the art.

We claim:

1. In combination with a container provided with a peripheral groove adjacent to but spaced from the base thereof, a suspension device for said container adapted to dispose said container in a mouth-downward position, comprising a wire band mounted in said groove, the end portions of said band being secured together to form a hoop in said groove, and a flat bail member slidably clamped to said container by said band, said bail member being provided with enlarged end portions permitting the said end portions of said bail member to be locked in place under said band, whereby, when said container is suspended by said bail member, the flat sides of the bail member grip the container wall about the base thereof and restrain the container against twisting movement.

2. A combination of the character set forth in claim 1, wherein the said flat bail member is of substantially uniform width throughout its length and the said enlarged end portions are provided by thickening the bail member at the ends thereof and wherein the thickened end portions taper inwardly from the ends thereof.

3. In combination with a container for the dispensing of parenteral fluids, said container being provided with

5 a peripheral recess adjacent to but spaced from its base, a suspension device comprising a wire band mounted in said recess and having a length greater than the peripheral length of said recess, the overlapping end portions of said band being welded together to form the band into a hoop, said peripheral recess being wider at one point to permit access of means for welding together the said overlapping end portions of the band, and a positionable resilient bail member clamped to said container by said band, said bail member being in the form of a flat strip of considerably greater width than thickness, said bail member being provided with an enlarged end portion of an outwardly-tapering thickness to permit said bail member to be slidably anchored within the groove beneath said wire band and whereby, when the container is suspended by said bail member, the flat sides of said bail member grip the container wall about the base thereof and restrain the container against twisting movement.

20 4. In a parenteral solution container equipped with a closure and adapted to dispense parenteral liquid from a mouth-downward position, said container being provided with a peripheral groove adjacent to but spaced from the base of said container, said groove being in the form of a spiral and enlarged laterally at least one portion, a suspension device for said container comprising a wire mounted in said groove, said wire having a length greater than the peripheral length of said groove whereby said wire has overlapping end portions when mounted in said groove, said wire being so positioned in said groove that said overlapping end portions are welded together in said laterally-enlarged portion, and a flat strap bail slidably clamped to said container by said wire, said bail member being provided with thickened end portions to permit secure anchoring of said bail member under said wire within said groove.
